US0D1064586S

(12) **United States Design Patent** (10) **Patent No.:** **US D1,064,586 S**
(45) **Date of Patent:** **** Mar. 4, 2025**

(54) **TRUNK**

- (71) Applicant: **DB Equipment AS**, Oslo (NO)
(72) Inventors: **Truls Kristian Brataas**, Oslo (NO);
Hunter Nordhauser, Oslo (NO)
(73) Assignee: **DB Equipment AS** (NO)
(**) Term: **15 Years**
(21) Appl. No.: **29/958,497**
(22) Filed: **Aug. 20, 2024**

Related U.S. Application Data

- (62) Division of application No. 35/518,979, filed on Oct. 24, 2023 (U.S. filing date under 35 U.S.C. 384), and having an international filing date of Oct. 24, 2023.
